COLLAPSIBLE GANTRY

Benjamin Jacoby and John M. Quigley, Marion,
Ohio, assignors to The Marion Steam Shovel
Company, Marion, Ohio, a corporation of
Ohio (Incorporated in 1927)

Application October 17, 1936, Serial No. 106,151

24 Claims. (Cl. 212—59)

This invention relates to a collapsible gantry for excavating machines or other machines having booms.

The ordinary excavating machine has a forwardly and upwardly inclined boom which is usually supported at a fixed inclination but which is adjustable to different inclinations according to the demands of the work. This boom is supported from a gantry, sometimes called an A-frame, which is mounted on the platform of the machine, usually by means of a cable which is connected with the point of the boom and extends about a sheave on the gantry to a hoisting drum on the platform, whereby the vertical movement of the boom may be controlled and it may be adjusted to the desired inclination. The height of this gantry is limited by the fact that the machine in traveling from one point to another must pass under overhead structures, wires and the like which would obstruct the movement of a high gantry. The ordinary gantry provides a satisfactory support for the boom in its higher elevations but when the boom is lowered to a position in which its point is near the level of the top of the gantry the cable comes so nearly parallel to the boom that it does not provide a satisfactory support and it places the boom under relatively great compression stresses. It is therefore highly desirable, particularly in the case of booms of relatively great length, to provide a gantry of such height that the cable will extend at such an angle to the boom, in all positions of the latter, as to provide a satisfactory support therefor and to avoid undue stresses.

It is the primary object of my invention to provide a gantry of relatively great height which will be collapsible to permit it to pass under any overhead structure under which the usual gantry could pass.

A further object of the invention is to provide a collapsible gantry of such a character that it can be easily and quickly collapsed to permit the machine to pass under an overhead structure and then quickly and easily restored to its extended position.

A further object of the invention is to provide a collapsible gantry of such a character that it will support the boom while in its collapsed condition, thereby permitting the machine and the boom, as a whole, to be moved under the overhead structure.

A further object of the invention is to provide a collapsible gantry the several parts of which will be so constructed and arranged that no part of the structure can contact with the boom in

any position to which the gantry may be moved.

A further object of the invention is to provide a gantry of such construction that it may be installed on existing machines by the addition of parts to the ordinary gantry, with little or no change in that gantry or other parts of the machine.

A further object of the invention is to provide such a collapsible gantry which will be simple in its construction, of a strong rigid character and which may be produced at a relatively low cost.

Other objects of the invention may appear as the device is described in detail.

In the accompanying drawings Fig. 1 is a side elevation of the forward portion of a dragline excavator, partly broken away, showing a collapsible gantry installed thereon; Fig. 2 is a side elevation of a portion of the machine, partly broken away, showing the boom supported in an elevated position by the partly collapsed gantry; and Fig. 3 is a transverse section of the gantry taken on the line 3—3 of Fig. 1.

In these drawings we have illustrated one embodiment of our invention and have shown the same as applied to a dragline excavator of a well known construction but it will be understood that this embodiment of the invention has been chosen for the purpose of illustration only and that the gantry may take various forms and may be applied to excavating machines or other machines of various kinds, without departing from the spirit of the invention.

The machine here shown is a dragline of ordinary construction and comprises a base 10 carried by suitable traction devices 11 and having 35 mounted thereon a rotatable platform 12 on which the various parts of the excavating mechanism are mounted, the machinery being enclosed in a housing 13. A boom 14 is mounted at its foot upon the platform 12 and an excavating 40 scoop 15 is supported from the point of the boom by a cable 16 which extends about a sheave 17 on the boom and thence rearwardly to the platform where it is wound on a power operated drum, which is not here shown but which is 45 mounted on a shaft 18. The scoop is moved through the material to be excavated, toward the machine, by a drag cable 19 connected with the open end of the scoop by means of a bridle 20 and wound on a power operated drum also 50 mounted on the shaft 18. The two drums are separately operable to first fill the scoop and then hoist the same to permit it to be moved to dumping position by swinging the boom.

The boom is supported at the desired inclina- 55

tion by means of a cable 22 connected with the boom and extending about a sheave on a gantry to a hoisting drum 23 which controls the movements of the cable and thereby the position of the boom. In order that the cable may be supported at a sufficient height to maintain the same at a relatively broad angle to the boom in all positions of the latter without interfering with the movement of the machine as a whole beneath overhead structures, we have provided a collapsible gantry, the upper portion of which may be collapsed or folded to a position in which it will not interfere with the passage of the machine beneath such overhead structures. As here shown, the gantry comprises a lower or base structure mounted on the platform 12 and, in the present instance, consisting of an upright member 24, here shown as slightly inclined, and a forwardly and downwardly extending member or brace 25 which is connected at its upper end with the upright member 24 and at its lower end with a fixed part on the platform 12. The members 24 and 25 may be of any suitable construction but preferably each member comprises a pair of upright bars spaced laterally one from the other, as shown in Fig. 3. This base structure is provided at its upper end with a sheave 26 which is preferably mounted on a shaft 27 carried by the upper portion of the base structure and which, in the present instance, also serves to connect the members 24 and 25 one with the other. The base structure as here shown is substantially identical with the gantry with which such a machine is usually provided and such ordinary gantry may, if desired, be utilized as the base structure of the collapsible gantry, or a separate base structure may be provided. In the present construction the collapsible parts of the gantry are of such a character that they may be mounted on the ordinary rigid gantry, thus enabling that gantry to be converted into a collapsible gantry by the addition of the collapsible parts thereof, which may be done in the field without the necessity of returning the machine to the shop, as little or no change in construction is required.

The upper or collapsible portion of the gantry comprises a supporting member 28 which extends upwardly from the base structure and is so mounted thereon that it can be moved from an upright position above the base structure to a position in which it will not extend above the top of the base structure. Preferably this supporting member is pivotally mounted at its lower end on the base structure and, in the arrangement shown, it comprises two pairs of bars spaced one from the other and pivotally mounted on the shaft 27 near the respective ends thereof. Any suitable means may be provided for normally locking this supporting member in its extended or upright position but preferably this means is in the form of a brace extending from the upper portion of the supporting member to a fixed support on or adjacent to the platform 12. In the construction shown this brace comprises two members 29 and 30 which are normally aligned one with the other to provide a rigid brace but which are pivotally connected one to the other and with the supporting member and a stationary part of the machine in such a manner as to permit them to fold one toward the other and thereby cause the supporting member to move about its axis. In the present instance each brace member comprises two bars spaced laterally one from the other and the adjacent ends of the cor-

responding bars of the two members are pivotally connected one to the other, as shown at 31. The bars may be of any suitable character but are preferably hollow and rectangular in cross section, as shown in Fig. 3, to provide ample strength to withstand the compression stresses to which they are subjected. The upper ends of the bars of the upper brace member 29 are pivotally mounted on a shaft 32 mounted on the upper end of the supporting member 28 and the lower ends of the two bars of the lower brace member 30 are pivotally mounted at 33 on parts of the base structure adjacent to the platform 12. The upper brace member 29 is provided with short arms 34 which extend downwardly below the pivot point 31 and are provided with lugs 35 which overhang the forward side of the lower brace member 30 to prevent the connected ends of the two members from moving rearwardly beyond other aligned positions. Suitable means are provided for positively holding the brace members normally against forward movement, this means being preferably interposed between the brace and the base structure of the gantry. As here shown, tie bars or links 36 are pivotally mounted on the shaft 27 of the base structure and are detachably connected with the lower brace member 30, as by means of pins 37 extending through lugs 38 carried by that brace member and removable therefrom to permit the forward movement of the brace members about their axes. The gantry is provided at the upper end of the supporting member 28 with a sheave 39, preferably mounted on the shaft 32, about which the boom cable 22 extends. Usually this boom cable is dead ended on the supporting member 28, as by rigidly securing the end thereof to a connecting device 40 pivotally mounted on the shaft 32. The cable then extends forwardly about a sheave 41 near the point of the boom, and then rearwardly about the sheave 39 and downwardly to the hoisting drum 23. The cable may be reeved back and forth between the connecting device and the point of the boom any suitable number of times by providing the boom with additional sheaves 41 and mounting horizontal sheaves on the connecting device but so far as the present invention is concerned it is immaterial how the cable is mounted so long as it is connected with the boom and extends about the sheave on the gantry.

It will be apparent that the two part brace constitutes a toggle which, when in its extended position, rigidly retains the supporting member 28 in its upright or operative position. When this supporting member is to be lowered or collapsed the toggle is broken by moving the connected ends of the two brace members forwardly, thereby causing the brace members to fold one toward the other and permitting the supporting member to move to a more or less horizontal position. The sheave 39 is so arranged with relation to the sheave 26 on the base structure that the forward movement of the upper sheave 39 will cause the boom cable 22 to engage the sheave 26 and the load on the cable will be transferred to the sheave 26 and the base structure, a guide 42 being provided to cause the cable to properly engage the sheave 26. The supporting member 28 then moves into alignment with that portion of the boom cable between the connecting device 40 and the point of the boom and thereafter serves merely as a part of the means for connecting the cable with the base structure of the gantry, and the cable can be

operated over the lower sheave 26 to control the position of the boom in the same manner that it would be operated if the extension or collapsible elements were not present.

- 5 When the gantry is to be collapsed the boom may, if desired, be lowered to support the point thereof on the ground, or other suitable support, or the gantry may be collapsed while the boom is supported by the boom cable 22. If the 10 boom is lowered onto a support the load on the boom cable is, of course, relieved and when the toggle is moved to its releasing position the movable parts of the gantry will move downwardly by gravity, the drum 23 being operated to take up 15 the slack in the boom cable as the supporting member 28 and its sheave 39 move downwardly. When the gantry is collapsed while the boom is supported by the cable 22 the drum 23 is operated to slowly lower the boom, after the brace has 20 been released, and the movable parts of the gantry will move downwardly with the boom. To prevent the too rapid collapsing of the gantry, which might cause injury to parts of the machine, we prefer to provide means for retarding 25 that movement, such as a cable connected with the brace and with a power operated drum, so that the collapsing movement of the gantry may be retarded by slowly paying out the cable and the gantry may be restored to its extended position 30 by winding in the cable. To avoid the necessity of providing an additional cable and operating mechanism therefor the dragline cable 19 may be used as a retarding and restoring cable by disconnecting the same from the bridle 20 of 35 the scoop, passing the same over a sheave 43 on the shaft 27 of the base structure and connecting the same with a bridle 44 on the lower brace member 30. The drag cable is usually connected with the bridle 20 by means of a 40 socket 45 in which the end of the cable is secured by a wedge in the ordinary manner. Inasmuch as this socket will not pass between the sheaves of the fair lead 46 it is preferable to remove the wedge and disconnect the cable from 45 the socket 45 and to then connect the same with the bridle 44 of the brace member by wedging the end thereof in a similar socket 47 on the bridle 44.

When the boom has been lowered onto a 50 port and the gantry collapsed the point of the boom may be raised by the boom cable 22 to a slightly elevated position so that it will be wholly supported by the machine and the machine as a whole, including the boom, may be propelled 55 from one position to another. When the boom is supported on the ground the gantry may be restored to its extended position by winding in the retarding and restoring cable 19 and paying out the boom cable 22 to permit the collapsible 60 supporting member 28 to move to its upright position while the boom remains stationary. The boom when in its lowered position may be supported either on the ground or by the boom cable and it may be moved from its lowered 65 position to any desired elevation by the action of the boom cable. As the boom is elevated the movable parts of the gantry will move with the boom toward their extended positions, and the movement of the gantry to its fully extended position 70 may be completed either by the retarding and restoring cable or by the boom.

A considerable force is required to move the 75 two members of the brace about their axis 31 to break the toggle, especially when the weight of the boom is supported by the cable 22 and

the gantry. It is therefore desirable to provide some means for imparting this initial movement to the brace members. This may be conveniently done by means of a small jack interposed between one of the brace members and a relatively stationary part. We have here shown such a jack in the form of a turnbuckle 48 which is pivotally mounted at one end on the base structure of the gantry and at its other end engages the lower brace member 30 when the latter is in 10 its operative position but is detachably connected with that brace member to permit the latter to move with relation thereto after initial movement has been imparted to the brace.

It will be obvious from the foregoing description that when the gantry is in its collapsed or partially collapsed position the weight of the boom is carried by the base structure of the gantry and that the boom may be supported by the cable 22, operating over the sheave 26 in 20 any desired position and the excavating element can be operated while the boom is so supported, thereby enabling small excavating jobs to be done between successive movements of the machine without the necessity of restoring the gantry to its extended position, as shown in Fig. 2.

It is important that the collapsible elements of the gantry shall not contact with the boom in any position to which the boom and gantry may be moved. To prevent this the several parts 30 of the gantry must be carefully proportioned and the pivotal axes of the movable parts so arranged that the movable parts of the gantry, and particularly the connected ends of the two brace members, will at all times be spaced from the 35 boom. The proportions of the parts and the arrangement of the pivots as here shown are well adapted for this purpose but obviously the proportions may be changed and the arrangement of the pivots varied to accommodate the same to 40 different installations or to different embodiments of the invention.

While we have shown and described one embodiment of our invention we wish it to be understood that we do not desire to be limited to the 45 details thereof as various modifications may occur to a person skilled in the art.

Having now fully described our invention, what we claim as new and desire to secure by Letters Patent, is:

1. In a machine comprising a boom, a cable to support said boom, and means for taking in or paying out said cable to raise or lower said boom, a gantry including a stationary structure and a member mounted on said stationary structure for movement thereon from an elevated position to a lower position, a sheave carried by said movable member, and means for retaining said movable member normally in said elevated position with said sheave in supporting 60 engagement with said cable, said retaining means including a part which is movable while said cable is supported on said sheave to release said movable member for downward movement under the weight of the boom acting thereon through 65 said cable.

2. In a machine comprising a boom, a cable to support said boom, and means for taking in or paying out said cable to raise or lower said boom, a gantry including a stationary structure 70 and a member mounted on said stationary structure for movement thereon from an elevated position to a lower position, a sheave carried by said movable member, and releasable means for retaining said movable member normally in said 75

- 5 elevated position with said sheave in supporting engagement with said cable, said movable member being so arranged that when released from said retaining means it may move downwardly either during the downward movement of said boom or while said boom is supported independently of said cable.
- 6 3. In a machine comprising a boom, a cable to support said boom, and means for taking in or paying out said cable to raise or lower said boom, a gantry including a stationary structure and a member mounted on said stationary structure for movement thereon from an elevated position to a lower position, a sheave carried by said movable member, and means for retaining said movable member normally in said elevated position with said sheave in supporting engagement with said cable, said retaining means including a part which is movable while said cable is supported on said sheave to release said movable member for downward movement, and means to control the movement of said movable member.
- 7 4. In a machine comprising a boom, a cable to support said boom, and means for taking in or paying out said cable to raise or lower said boom, a gantry including a stationary structure and a member mounted on said stationary structure for movement thereon from an elevated position to a lower position, a sheave carried by said movable member, and means for retaining said movable member normally in said elevated position with said sheave in supporting engagement with said cable, said retaining means including a part which is movable while said cable is supported on said sheave to release said movable member for downward movement, and a sheave carried by said stationary structure and arranged to receive said cable as said movable member moves downwardly.
- 8 5. In a machine comprising a boom, a cable to support said boom, and means for taking in or paying out said cable to raise or lower said boom, a gantry having a movable member, a sheave carried by said movable member, releasable means for retaining said movable member normally in an elevated position with said sheave in supporting engagement with said cable, said movable member being so mounted that when released from said retaining means it may move downwardly either during or subsequent to the downward movement of said boom, and means to control said downward movement of said movable member.
- 9 6. In a machine comprising a boom, a cable to support said boom, and means for taking in or paying out said cable to raise or lower said boom, a gantry having a movable member, a sheave carried by said movable member, releasable means for retaining said movable member normally in an elevated position with said sheave in supporting engagement with said cable, said movable member being so mounted that when released from said retaining means it may move downwardly either during or subsequent to the downward movement of said boom, and means acting on said movable member to retard its downward movement and to restore the same to its elevated position.
- 10 7. In a machine comprising a boom, a cable to support said boom, and means for taking in or paying out said cable to raise or lower said boom, a gantry having a base and a member pivotally mounted on said base, a sheave carried by said pivoted member, and releasable means for
- 11 upright position with said sheave in supporting engagement with said cable, said pivoted member being so arranged that when released by said retaining means it may move toward a horizontal position while said boom moves downwardly under the control of said cable.
- 12 8. In a machine comprising a boom, a cable to support said boom, and means for taking in or paying out said cable to raise or lower said boom, a gantry having a base and a member pivotally mounted on said base, a sheave carried by said pivoted member, releasable means for normally retaining said pivoted member in an upright position with said sheave in supporting engagement with said cable, said pivoted member being so arranged that when released by said retaining means it may move toward a horizontal position while said boom moves downwardly under the control of said cable, and a sheave carried by said base and arranged to receive said cable as the first mentioned sheave moves toward said horizontal position.
- 13 9. In a machine comprising a boom, a cable to support said boom, and means for taking in or paying out said cable to raise or lower said boom, a gantry having a base and a member pivotally mounted on said base, a sheave carried by said pivoted member, releasable means for normally retaining said pivoted member in an upright position with said sheave in supporting engagement with said cable, said pivoted member being so arranged that when released by said retaining means it may move toward a horizontal position while said boom moves downwardly under the control of said cable, and means to control the movement of said pivotal member about its pivotal axis.
- 14 10. In a machine comprising a boom, a cable to support said boom, and means for taking in or paying out said cable to raise or lower said boom, a gantry having a base and a member pivotally mounted on said base, a sheave carried by said pivoted member, releasable means for normally retaining said pivoted member in an upright position with said sheave in supporting engagement with said cable, said pivoted member being so arranged that when released by said retaining means it may move toward a horizontal position while said boom moves downwardly under the control of said cable, and a cable acting on said pivoted member to retard its downward movement and to thereafter restore the same to its upright position.
- 15 11. In a machine comprising a boom, a cable to support said boom, and means for taking in or paying out said cable to raise or lower said boom, a gantry having a member pivotally mounted for movement from an upright position toward said boom, a sheave carried by said member, and a toggle brace for rigidly supporting said member in said upright position with said sheave in supporting engagement with said cable, said toggle brace being so arranged that the breaking of the toggle will permit said member to move downwardly toward said boom.
- 16 12. In a machine comprising a boom, a cable to support said boom, and means for taking in or paying out said cable to raise or lower said boom, a gantry having a member pivotally mounted for movement from an upright position toward said boom, a sheave carried by said member, a toggle brace for rigidly supporting said member in said upright position with said sheave in supporting engagement with said cable, said toggle brace being so arranged that the breaking

of the toggle will permit said member to move downwardly toward said boom, and means acting on said toggle brace to control the downward movement of said pivoted member.

- 5 13. In a machine comprising a boom, a cable to support said boom, and means for taking in or paying out said cable to raise or lower said boom, a gantry having a member pivotally mounted for movement from an upright position 10 toward said boom, a sheave carried by said member, a toggle brace for rigidly supporting said member in said upright position with said sheave in supporting engagement with said cable, said toggle brace being so arranged that the breaking 15 of the toggle will permit said member to move downwardly toward said boom, and means acting on said toggle brace to break the toggle and release said pivoted member.

14. In a machine comprising a boom, a cable 20 to support said boom, and means for taking in or paying out said cable to raise or lower said boom, a gantry having a base and a member pivotally mounted on said base for movement from an upright position toward said boom, an upper sheave carried by said pivoted member, a lower sheave carried by said base, a toggle brace 25 to normally support said pivoted member in an upright position with said upper sheave in supporting engagement with said cable, means to 30 break said toggle and release said pivoted member for downward movement toward said boom, said movement of said pivoted member causing said cable to have supporting engagement with said lower sheave, and means acting on said 35 toggle brace to retard the downward movement of said pivoted member.

15. In a machine comprising a boom and a cable to control the vertical movement of said boom, a gantry having a base and a member 40 pivotally mounted on said base for movement from an upright position toward said boom, an upper sheave carried by said pivoted member, a lower sheave carried by said base, a toggle brace 45 to normally support said pivoted member in an upright position with said upper sheave in supporting engagement with said cable, means to break said toggle and release said pivoted member for downward movement toward said boom, said movement of said pivoted member causing 50 said cable to have supporting engagement with said lower sheave, a cable connected with said toggle brace, and power controlled means acting on said cable to retard the downward movement of said pivoted member and to thereafter extend 55 said toggle brace and restore said pivoted member to its upright position.

16. In a machine comprising a boom, a hoisting drum and a cable connecting said hoisting drum with said boom to control the vertical 60 movement of the latter, a gantry having a movable member, a sheave carried by said movable member, releasable means for normally retaining said movable member in an elevated position with said sheave in supporting engagement with 65 said cable and for releasing said movable member for downward movement, means cooperating with said cable to enable the latter to control the position of said boom after downward movement has been imparted to said movable member, and means to control the movement of said 70 movable member.

17. In a machine having a platform and a boom, a gantry comprising a base structure carried by said platform, a supporting member pivotally mounted on said base structure for move-

ment from a normally upright position toward said boom, a sheave carried by said supporting member, a hoisting drum on said platform, a cable connected with said boom and extending about said sheave to said drum, a brace to retain said 5 supporting member in its upright position, said brace having two parts pivotally connected one with the other, one part of said brace being pivotally connected with said supporting member and the other part of said brace being pivotally connected with a normally stationary part of said machine, whereby the movement of the connected ends of said parts of said brace toward said boom will permit said supporting member to move toward a horizontal position, and means 10 to retard the movement of said brace and said supporting member.

18. In a machine having a platform and a boom, a gantry comprising a base structure carried by said platform, a supporting member pivotally mounted on said base structure for movement from a normally upright position toward said boom, a sheave carried by said supporting member, a hoisting drum on said platform, a cable connected with said boom and extending about said sheave to said drum, a brace to retain said supporting member in its upright position, said brace having two parts pivotally connected one with the other, one part of said brace being pivotally connected with said supporting 20 member and the other part of said brace being pivotally connected with a normally stationary part of said machine, whereby the movement of the connected ends of said parts of said brace toward said boom will permit said supporting member to move toward a horizontal position, a second drum carried by said platform, a cable wound on said second drum, and means for connecting said cable with said brace to control the 25 movements thereof.

19. In a machine having a platform and a boom carried by said platform, a collapsible gantry comprising a base structure on said platform, a normally upright supporting member pivotally mounted on said base structure, means for establishing supporting connection between said boom and said member when the latter is in its upright position, and a brace connected at its respective ends with said supporting member and with a stationary part of said machine and comprising two aligned members having their adjacent ends pivotally connected one to the other and movable toward said boom to collapse said gantry, the several parts of said gantry being so proportioned and having their pivotal axes so arranged that the connected ends of said brace members will be supported out of contact with said boom in all operative positions of said boom and said brace.

20. In a machine having a platform and a boom carried by said platform, a collapsible gantry comprising a base structure on said platform, a normally upright supporting member pivotally mounted on said base structure and movable toward said boom, means for establishing supporting connection between said boom and said member when the latter is in its upright position, and a brace connected at its respective ends with said supporting member and with a stationary part of said machine and comprising two aligned members having their adjacent ends pivotally connected one to the other and movable toward said boom to collapse said gantry, and detachable means for rigidly connecting said brace with said base structure to 70

retain said brace members in their alined positions.

21. In a machine having a platform and a boom carried by said platform, a collapsible gantry comprising a base structure on said platform, a normally upright supporting member pivotally mounted on said base structure, means for establishing supporting connection between said boom and said member when the latter is in its upright position, and a brace connected at its respective ends with said supporting member and with a stationary part of said machine and comprising two alined members having their adjacent ends pivotally connected one to the other and movable toward said boom to collapse said gantry, and a device interposed between said base structure and said parts and acting on the latter to impart initial movement thereto.
22. In a dragline excavator comprising a platform, a boom carried by said platform, an excavating scoop, a cable to support said scoop from the point of said boom, a drag cable to impart excavating movement to said scoop and power operated drums on said platform to operate said cables, a collapsible gantry including a base structure, a normally upright supporting member pivotally mounted on said base structure, a foldable brace having alined members pivotally connected one with the other and pivotally connected respectively with said supporting member and with a stationary part on said platform, a sheave on said base structure adapted to receive said drag cable when the latter has been detached from said scoop, means for connecting said drag cable with said brace to control the movements thereof, a sheave on said supporting member, a cable connected with said boom and extending about the last mentioned sheave, and

means on said platform for controlling the movements of the last mentioned cable.

23. An attachment for a machine having a platform, a boom, a hoisting drum, a gantry, a sheave carried by said gantry and a cable connected with said boom and extending about said sheave to said drum, said attachment comprising a supporting member adapted to be pivotally mounted on said gantry, a brace connected at one end with said supporting member and having at its other end means for connecting the same with a stationary part of said machine to retain said supporting member in an upright position, said brace being movable with relation to said supporting member to permit the latter to move from said upright position, and a sheave carried by said supporting member and adapted to receive and support said cable when said supporting member is in its upright position and so arranged that said cable will be automatically transferred therefrom to the sheave on said gantry when said supporting member moves from its upright position.

24. In a lifting machine, a carriage, a cab mounted to turn about a vertical axis over the carriage, a boom at the front of the cab, a mast rising from the cab back of the boom and comprising a lower section of substantially A-frame formation, an upper section having its lower inner end pivoted to the upper end of the lower section, and a support for the upper section rising from the carriage between the boom and the lower section and comprising movable parts connected one to the other for relative movement to collapsed positions.

BENJAMIN JACOBY.
